UNITED STATES PATENT OFFICE

CLARENCE W. MOORE, OF ROSLYN, PENNSYLVANIA, ASSIGNOR TO RITTER DENTAL MANUFACTURING COMPANY, INC., OF ROCHESTER, NEW YORK, A CORPORATION OF DELAWARE

FOUNTAIN CUSPIDOR

Original application filed November 30, 1926, Serial No. 151,736. Divided and this application filed September 5, 1929. Serial No. 390,487.

This invention relates to fountain cuspidors, with particular reference to cuspidors used in the professions, such as dentistry and medicine.

The subject matter disclosed and claimed herein constitutes a division of an application for fountain cuspidors, filed Nov. 30, 1926, Ser. No. 151,736, patented April 15, 1930, No. 1,754,757.

10 In the application above identified there was disclosed a fountain cuspidor of novel construction and possessed of numerous advantages over the prior art. In its simplified and preferred form the cuspidor comprised a unitary drainage and distributing head through which all of the water and waste of the cuspidor passed. A bowl was mounted on the upper end of the head, while the lower portion of the head engaged with a support housing drainage and water supply passages or conduits, while a branch extended laterally and upwardly from the head carrying a tumbler bowl and its associated supply and drainage passages.

25 Among the objects of the invention are: to provide improvements in valve constructions for cuspidors; to provide in a cuspidor a supply or distributing head of a single unitary casting; to reduce the labor formerly necessary in constructing cuspidors; to provide an improved method of forming and assembling valves in cuspidors; to provide the control valves of cuspidors as pre-formed inserted units; and many other objects and advantages as will be more apparent as the description proceeds.

30 Before describing the invention in detail it should be noted that among other items of expense in former constructions of cuspidors, was the labor cost in the formation of the ducts, conduits and similar water passages to and from the valves controlling the several water supply passages. The former constructions required accurate machining and drilling, to allow for which castings used were heavy, with thick walls, accounting for appreciable expense for the material alone, and the labor cost added to the cost of material formed an expensive element in the total cost. In large measure both of

these features of expense have been reduced in the present invention.

In the accompanying drawings;

Fig. 1 represents a side elevation of the unitary head, partially broken away at the base, and showing the location of the several ducts, conduits and passages in dotted lines. 55

Fig. 2 represents another side elevation of the same and showing the branch coupling 60 face,

Fig. 3 represents still another side elevation of the same, with the supply pipes or tubes shown in dotted lines, and showing the disposition of the valves. 65

Fig. 4 represents a top plan of the same, partially broken away to show the embedded supply tubes,

Fig. 5 represents a fragmentary section through a wall of the unitary head, disclosing the formation and assembly of a valve controlling a water supply tube. 70

Fig. 6 represents a fragmentary section through a wall of the unitary head to disclose the construction of the valve controlling the flow of water through the ejector, with the ejector tube shown in dotted lines. 75

Fig. 7 represents a top plan of a pre-formed valve seat and supply tube assembly. 80

Fig. 8 represents a side elevation of the same,

Fig. 9 represents another side elevation of the same.

In constructing the cuspidor compactness 35 and economy were among the desiderata, and the cuspidor affords both. In the preferred form of head, through which all of the drainage from the several elements of the cuspidor passes, as well as the entire 90 water supply for the assembly, it was desired that economy as to metal used as well as economy in subsequent machining operations be employed. Such economies were achieved by the invention of a structure susceptible to formation by a casting operation. As so formed, the valves controlling the water supply are pre-formed and mounted in the head in a novel manner, and water supply conduits from the valves to the sev- 95 100

eral outlets are formed by pre-formed tubes cast in the metal of the head. Drainage from the tumbler bowl and from the saliva ejector is into the drainage passage of the head, beneath the cuspidor bowl and its associated trap.

The head B, preferably a casting, comprises a hollow sleeve-like body, terminating at the lower end in a threaded coupling member 16, and at the upper end in a bowl coupling member 17. Both coupling members are preferably concentric with the axis of the head. The major portion of the main body of the head is generally annular or cylindrical and is concentric with its axis and with the coupling members, but at one side is provided with a branch coupling face 18, having threaded openings 19 to receive coupling screws of the branch, and on another side, preferably diametrically opposite thereto, the head is provided with a radial projection 20. The wall 21 from which the projection 20 extends is formed of appreciable thickness, having a substantially plane inner face 22, and the wall 23, contiguous to the branch coupling face, and opposite to wall 21, has also a substantially plane inner face 24, parallel with the inner face 22. The thickened walls 21 and 23 are connected by the curved relatively thin walls 25 and 26, having the irregularly curved inner surfaces 27 and 28 respectively. The inner faces 22 and 24, and 27 and 28, form the main drainage passage 29 through the head, and which is generally trapezoidal in outline. The drainage passage 29 thus formed is of substantially uniform diameter from the upper end of the head to well toward the bottom, where an oblong slot 30 pierces the wall 23 from inner face 24 to the surface of the branch coupling face 18, to permit the passage of drainage water from the branch. Beneath the slot 30, the area of the drainage passage 29 is decreased by a web 31 projecting inwardly from the several inner faces of the walls to form the common circular outlet 32, concentric with the axis of the head. It will be noted however, that although the common outlet 32 is concentric with the axis, the major area of the main drainage passage 29 is located laterally of the axis of the head as located by the outlet 32 and coupling members 16 and 17, due to the differing thicknesses of the walls of the head.

For supplying water to the conduits in the branch, to be described later, conduits 33 and 34 are provided in the head, extending from the thickened wall 21, through walls 25 and 26 respectively, and terminating in wall 23. The conduits 33 and 34 comprise tubes, pre-formed and curved so that in position the ends located in wall 21 are arranged in parallel spaced horizontal relation, and in wall 23 are in spaced

relation out of vertical alignment, to permit coupling with conduits in the branch, to be described.

The tubes 33 and 34 terminate in metal valve seat inserts 35 and 36 respectively, with which they are held in proper association during the casting operation, and which form integral parts of the metal walls after such operation. Each valve seat insert comprises a disc of metal knurled at its periphery as at 37, to facilitate the grip of the cast metal thereon, and each has an axial bore 38 and a concentric valve seat 40 formed on one face. The disc insert is associated with the pre-formed tube prior to the casting operation, and it is preferred to drill a hole 41 part way through the disc insert from the rear face, close to the axial bore 38, of such diameter as to receive an end of the bent tube to be associated with it. The end of the tube is inserted in the hole 41 and held against movement therein as by means of silver solder, for instance. This leaves a thin web of disc metal 39 between the open end of the tube and the valve side of the insert, which precludes entrance of cast metal into the tube during the casting operation. This construction is preferred as it enables the use of a valve of restricted size compared with the diameter of the tube through which the water is to pass. It will be clear, however, that it is not necessary to leave the thin web of metal 39 over the end of the tube, but that the tube may be inserted into a hole drilled all the way through the disc, and a removable element associated with the end thereof during the casting, and which is withdrawn with the core, (not shown). However associated, the tubes 33 and 34 are held in position with the disc inserts or valve seats 35 and 36, during the casting, in which metal flows about and embraces the rear face, the periphery and the outer portion of the valve seat face of the inserts, as well as the entire tube, but leaving a cylindrical threaded bore or chamber 42 adjacent the valve seat face.

The thickened wall 21 is of such size as to allow for the firm anchoring and embedding of the valve seat inserts and tubes, with sufficient metal beyond the valve to permit the firm support of an inserted valve stem 43, the threads 44 being formed in the valve chamber or bore 42 to receive the valve stem. In the form of valve assembly shown, to form a complete conduit from the valve chambers to the water supply tubes it is but necessary to drill passages 45 through the thin webs of disc metal over the ends of the respective tubes, preferably at an angle to the bore of each disc. It will be clear that water brought by passages to be described to the rear face of the disc seat of either valve, will pass through the axial

bore, and if the valve is unseated will flow into the valve chamber, through passage 45 into the tube. It will be understood that as far as the valve construction is concerned 5 it is identical for either tube 33 or 34, and the tubes are practically the same, except that they are bent in opposite directions, so that tube 33 is embedded in wall 25, while tube 34 is embedded in wall 26. In casting 10 the tubes in position, the ends remote from the valves may be prolonged in wall 23 until practically flush with face 18, and by a subsequent drilling operation they are terminated in tapering threaded openings 33' and 15 34' in the face 18.

Each valve chamber 42 is closed by a threaded nipple 46 extending thereinto, in engagement with the threads 44, through which nipple the valve stem 43 extends, the 20 inner end of which carries at 47 a freely rotatable cup 48, in which a resilient valve disc 50 is mounted, arranged for axial engagement with the seat 40. A handle or knob 51 is connected at the outer end of the 25 valve stem 43 in any desired manner, and the whole valve assembly is rendered watertight by a packing gland 52, as is well known. The valve assembly applies equally well to either valve controlling the passage 30 of water through the conduits 33 and 34. The control devices, the knobs or handles 51 and a part of the valve stem 43 extend beyond the outer periphery of the head above the radial projection and normal to a plane 35 surface 49 formed by shoulders 49' extending from the wall 21, and preferably in a horizontal plane. It will be noted that the tubes or conduits 33 and 34 are located and embedded in the walls of the body and do 40 not affect and are not affected by, the clearance of the drainage passage 29.

Depending from one side of the radial projection 20 is a saliva ejector housing 53, one portion of which is vertical, terminating 45 at the bottom in an ejector tube coupling 54, and axially drilled as at 55 to form a drainage passage intersecting at its upper edge as at 57, the upward bend of a saliva ejector passage or conduit 56. The saliva 50 ejector passage is a tube 56 as shown, which is of an inverted and widened V shape, located wholly in the wall 21 and the integral radial projection 20, in which latter it is located laterally of the center, in alignment 55 with the vertical drainage passage 55 in the housing. The outer end of the saliva conduit remote from the axis of the head or bore 59, and the conduit inclines upwardly 60 from the bore until its apex is in substantial alignment with the outer periphery of the head, when it inclines downwardly through the wall 21, terminating in a drilled opening 58 in the drainage surface 22. In forming 65 the ejector conduit, a pre-formed tube is

bent to the desired shape, and includes a hooked portion (not shown) arranged to turn up in the main drainage passage 29, by which hook it is supported during the casting operation. The upturned end may 70 subsequently be removed as by drilling, for which purpose a semi-cylindrical vertical groove 60 is provided in the inner face 22 as a guide for a drill, and the end of the tube and the adjacent metal, (not shown) 75 may be recessed by a horizontal drill passed horizontally through the lateral slot 30 in the head, which slot is in registry with the finished end of the saliva ejector conduit as shown.

A valve for the saliva ejector is formed in the substantial center of the radial projection 20 by embedding a pre-formed valve seat insert 61 in the projection. This insert is axially bored as at 62, and has a 80 concentric seat 63 formed thereon, and is held in proper vertical position during the casting operation by suitable core means, (not shown) extending into the bore 62, and preferably for a desired distance beyond the 85 insert to form a passage 69 coincident with the bore through which water passes to the valve seat. The insert is held horizontally by some such device as a set-screw 64 extended from a threaded opening 65 in the 90 insert, the outer end of which is gripped by portions of the die during the casting operation, and the projecting portion is later removed as by sawing until the end of the screw and the surface of the projection 20 95 are substantially flush, in the finished head. A valve chamber 66 is formed in the metal cast about the insert, including a threaded bore 67, to receive a valve 68, similar in all respects to those already described. The 100 water supply passage 69 formed as described or by suitable drilling, extends through the radial projection and wall 21 but does not enter nor communicate with the drainage surface 22, but terminates in substantial 105 alignment with the plane of the rear faces of the valve inserts 35 and 36, at such point as to intersect the main water supply duct to be described.

The saliva ejector tube, and the saliva 110 ejector valve are thus separated laterally by a wall of cast metal 70, and communication between them is had by a transverse duct 71, drilled from the ejector housing 53 to the valve chamber 66. The ejector end of the duct 71 is arranged in registry with a lateral opening 72 of the ejector 73, the tapered axial bore 74 of which terminates adjacent the intersection 57 of the saliva tube and saliva drainage passage 55. The ejector 115 has a threaded rear end 75, for receiving an ejector screw 76, closing the ejector bore 59. With the arrangement described water passing around the valve through the axial bore 69, enters the valve chamber 66, passes 120 125 130

through duct 71, and is projected from the ejector tip past or by the vertical saliva drainage conduit toward the apex of the tube, and then down to pass into the main drainage passage 29, where it merges with the other drainage material and passes out through the common outlet 32, and in passing exerts suction on the saliva drainage tube in the usual manner.

10. To supply water to the seat discs 35 and 36, two ducts are drilled, as at 88 and 89, from the upper portion of the head behind each valve seat disc respectively, converging upon the end of the water supply duct 77, at its intersection with the lateral bore 69. The outer ends of these ducts are plugged as desired.

I claim as my invention:

1. In a liquid distributing device an element having a liquid conduit, said conduit comprising a pre-formed arcuate tubular element completely embedded in the material of the element.

2. In a fluid distributing device an element having a fluid conduit and an integral valve seat, said conduit and valve seat comprising a pre-formed unit embedded in the material of the element said valve seat having a concentric bore, and said conduit engaging the valve seat eccentrically of the bore.

3. As an element arranged for embraced association with a liquid distributing device, a valve seat disc and a tube assembled as a unit.

4. In a liquid distributing device, an element having a valve, the valve including a pre-formed valve seat embedded in the material of the element the valve seat having a concentric bore and an inclined eccentric bore, and a pre-formed conduit engaging the valve seat and communicating with the said inclined bore.

5. In a fluid distributing element, a valve comprising a valve seat disc having a concentric bore and a valve seat surrounding the bore, the seat disc partially enclosed and embedded in the material of the element, said element having a chamber adjacent the seat, and a stem removably mounted in the chamber and carrying a valve arranged to engage the valve seat, said disc having a second bore laterally spaced from the first mentioned bore and out of registry with the valve stem.

In testimony whereof, I affix my signature.

CLARENCE W. MOORE.
